UNITED STATES PATENT OFFICE.

DANIEL COOK, OF PHILADELPHIA, PENNSYLVANIA.

WINDOW-SCREEN.

SPECIFICATION forming part of Letters Patent No. 361,136, dated April 12, 1887.

Application filed November 23, 1886. Serial No. 219,611. (No model.)

To all whom it may concern:

Be it known that I, DANIEL COOK, a citizen of the United States, residing at Philadelphia, in the county of Philadelphia and State of Pennsylvania, have invented certain new and useful Improvements in Window-Screens; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The special object of the invention is to improve that class of window-screens made in two sections connected by metallic clasps, so that one may slide upon the other.

Figure 1 of the drawings is a front elevation 20 of a screen, showing the screen open, and parts broken away. Fig. 2 is a horizontal section on line $x-x$ of Fig. 1; Fig. 3, a vertical section on line $y-y$ of Fig. 1; Fig. 4, an end elevation of the stile, showing the kerf; and Fig. 5, a 25 perspective view of the clasp.

In the drawings, A A represent the two sections of a window-screen, each provided with the net-work of wiring B, which is tacked on the rails. C are the inner and D the outer 30 stiles, E the rails, and F the clasps.

The clasps F are made of metal, with a drive-shank, f , flanged at f' , and a rail rest and guide, f'' , with a perpendicular flange, f^3 . The shank f is driven into a stile-kerf, G, which is made 35 in the vertex of the angle-rabbet g and in a downward direction.

In my Patent No. 315,249 the flange f^3 ex-

tends in an opposite direction from what it does in my present invention, so as to overlap and embrace the top of rail. In practice I 40 find this objectionable, as the impact of the window and its pressure upon this flange jams it upon the rail, so as to make it stick; hence I now reverse the flange f^3 , so as to make it simply a lateral guide, while the part f'' , which 45 stood parallel to the top of rail, now comes under the rail and forms a rest therefor, thus completely obviating the aforesaid objection.

By making the kerf G and the angular rabbet g , I greatly facilitate the application of 50 the clasps to the screens, lessen time and labor, and secure firmly by the use of a single nail, H, for each clasp; hence my clasp is differently constructed and also differently applied from what has been heretofore known to the 55 public, being let into the stile from the center, overlapping the bottom of rail, and rising in what may be termed a "groove" between the webbing and the stile.

Having thus described my invention, what I 60 claim as new, and desire to protect by Letters Patent, is—

A window-screen clasp made of metal, with a drive-shank, f , side flanged at f' , and a rest, f'' , having the perpendicular flange f^3 , projecting from the rest f'' in opposite direction to the drive-shank f , to adapt it to be used in 65 the manner described.

In testimony whereof I affix my signature in presence of two witnesses.

DANIEL COOK.
